UNITED STATES PATENT OFFICE.

NEAL LARKIN ANDERSON, OF MONTGOMERY, ALABAMA.

TYPE-WRITER.

SPECIFICATION forming part of Letters Patent No. 748,831, dated January 5, 1904.

Application filed August 24, 1903. Serial No. 170,546. (No model.)

To all whom it may concern:

Be it known that I, NEAL LARKIN ANDERSON, a citizen of the United States, residing at Montgomery, county of Montgomery, and State 5 of Alabama, have invented certain new and useful Improvements in Type-Writers; and I do hereby declare the following to be a full, clear, and exact description of the invention, such as will enable others skilled in the art to 10 which it appertains to make and use the same.

My invention relates to type-writing machines, and has for its object to provide motor mechanism for propelling the paper-carriage in both its advance and return movements and a primary power-driven motor adapted to be operatively connected with the propelling-motor to restore the energy of the latter which has been depleted by the operation of actuating the carriage.

The invention contemplates the employment of a motor, preferably a spring-motor, for advancing the carriage in the printing operation; reversing mechanism to couple said motor to the carriage to return the latter to its initial position, which coupling operation may be accomplished either automatically at some predetermined point or manually by the operator at any point in advance of that determined by the adjustment 25 of trip mechanism controlled by an auxiliary key, and a second motor, preferably an electric motor, that is started and coupled to the first-mentioned motor to restore the energy of the latter in the same operation that 30 couples the propelling-motor to the carriage for the return movement of the latter, said electric motor being automatically cut out of circuit when the energy of the propelling-motor has been restored.

In the accompanying drawings, illustrative of my invention, Figure 1 is a transverse sectional view of the motor mechanism applied to a Remington type-writing machine. Fig. 2 is a front elevation thereof. Fig. 3 is a 45 view corresponding to that of Fig. 1, but showing the operative relation of the motors during the return movement of the carriage. Fig. 4 is a front elevation thereof. Fig. 5 is a detail of the mechanism for operating the 50 electric switch mechanism during the return movement of the carriage. Figs. 6 and 7 are

detail views of the latch mechanism for holding the coupling between the power-wheel and the band-wheel out of engagement. Fig. 8 is a front elevation of the motor mechanism, showing the relation of the parts at the completion of the return movement. Fig. 9 is a detail of the latch for holding the reversing-gear in operative position during the return movement of the carriage. Fig. 10 is 60 an enlarged rear elevation of the circuit-controlling mechanism; and Fig. 11 is a front elevation showing the mode of applying the motor mechanism to a type-writing machine, and particularly illustrating the automatic 65 and manual trip mechanisms.

For the purpose of illustration I have shown the invention as applied to a Remington type-writing machine and have omitted from the drawings such parts of the machine 70 as are not necessary to illustrate the invention. It is to be understood, however, that the invention is adapted to any class of machines having a reciprocating paper-carriage, as will be obvious to those skilled in the art. 75

Referring to the drawings, 1, 2, and 3 indicate, respectively, the base, supporting-uprights, and the top plate of the frame of a Remington type-writing machine. Supported in suitable brackets at the rear left-hand 80 side of the machine is a shaft or arbor B, upon which is loosely mounted a drum E, provided with a flexible strap or band, connected at one end to the periphery of the drum and at the other to a projection on the lower side of 85 the paper-carriage Q. The drum and strap referred to occupy a position usually occupied by the spring-actuated drum of the ordinary Remington type-writer, and the drum turns upon the shaft in the same manner that the 90 usual drum turns during the reciprocation of the carriage. Said drum is provided with a ratchet-hub e^1 , which is engaged by a spring-pressed pawl e^2 of the character employed in the spring-drum of the Remington machine 95 to permit the tension of the spring f to be adjusted. The shaft B is provided with a collar f^2 , fast thereon, to which one end of a spiral spring f^1 is connected, the opposite end of said spring being connected to a gear-wheel 100 F, mounted loosely upon the collar f^2 . The outer periphery of the wheel F is provided

with gear-teeth, which are constantly in mesh with the teeth of a pinion t^4 , which is secured upon a shaft t , mounted in suitable brackets $m\ m'$ on the top plate of the machine, so that 5 said pinion is adapted to revolve freely upon said shaft, but is caused to partake of the horizontal movement of said shaft, as will be hereinafter explained.

Near the periphery of the wheel F are a 10 series of projecting pins h , which lie in a circular series within the rim of drum E . The drum E is provided with a coöperating pivoted pin h' , which is held in position by a spring z , so that said pin h' commonly occupies a 15 position to engage one of the pins h on wheel F , as indicated in Fig. 1.

Pivoted to the front face of drum E is a latch N^2 , provided with a squared shoulder adapted to pass over the projecting end of pin 20 h' and hold the latter out of coöperative relation with pins h when said pin h' has been depressed by mechanism to be described. A spring N^4 tends normally to force the latch N^2 into engagement with the pin h' .

Pivoted to one of the uprights of the 25 machine is a lever b^5 , to the other end of which is rigidly secured a crescent-shaped tripping-arm c^5 , normally lying above the path of movement of pin h' . Said lever b^5 is connected by a suitable link b^6 to an auxiliary key-lever b^7 .

Secured in the bracket m^3 on the lower side of the top plate 3 is a bell-crank lever R , which is connected by a link R' to the pivoted 35 bar b^5 . The upper end of said bell-crank lever has a pin-and-slot connection with sliding shaft t , which shaft is normally moved toward the front of the machine by a coiled spring s , bearing at one end upon bracket m and at the other end upon a suitable washer t^6 . Revolubly mounted upon the shaft t is a 40 gear t^8 , having a lateral clutch-face adapted to engage a corresponding clutch-face upon the pinion t^4 when said shaft t and said pinion t^4 are moved rearwardly. Gear t^8 meshes with a rack G , secured to the lower side of the carriage Q by means of the usual bracket-arms g , upon which the feed-rack is mounted. Pivoted to the bracket m is a latch N , which 45 is normally pressed against the shaft by means of a spring t^7 , as shown in Figs. 8 and 11. The latch N is notched on its edge adjacent to the shaft and is adapted to engage a circular notch f^8 on the shaft t when the latter is moved to the rear by the bell-crank lever R , so that said shaft will be held by the latch N in the position to which it is moved.

Mounted loosely upon the shaft B is a 50 toothed disk or gear C , which is constantly in mesh with a gear t' , loosely mounted upon shaft t . Pivoted to the face of said gear adjacent to gear t' is a pawl t^2 , engaging a ratchet t^5 , formed upon said gear t' . The relation of this pawl and ratchet is such that 55 when the carriage Q is moved forward in the printing operation the gear t' is rotated by

its engaging rack G , and pawl t^2 will idle upon the ratchet t^5 and no motion will be imparted to gear t' ; but when said gear t^2 is clutched to gear t' and revolved in the opposite direction the pawl t^2 , engaging the teeth of ratchet t^5 , will cause said gear t' to rotate in the same direction as gears $t^8\ t^4$ and impart a rotary movement to gear C . Secured to the rearward face of the gear C and insulated therefrom is a conductor-ring V^8 , upon which bears a spring contact or brush W^8 , mounted upon and insulated from the casing of an electric motor A . Mounted in the inner periphery of said ring V^8 is a fiber insulating-block W , 70 and at a short distance beyond this is a longer fiber block W' . Secured to the shaft B and partaking of the rotation thereof is a fiber disk U , to the outer edge of which is secured a conductor-ring U , which is engaged by a 75 second spring conductor or brush W^2 , mounted upon the motor-casing A . The disk U is provided with a radial perforation in which is mounted a spring-pressed brass pin X , which is held in contact with the ring V^8 or gear C , 80 so as to electrically connect conductor-rings V^8 and U' . Bolted to the face of the type-writer frame is a small electric motor A , the shaft A^2 of which is connected by reducing-gearing to shaft B . Said motor is driven from 85 a suitable source of power and may be of either the alternating or direct current type. The current, which is controlled by a suitable regulating-switch S in the bottom of the motor, is conducted from the binding-post a^7 to 90 contact spring or brush W^8 , thence to conductor-ring V^8 on gear C , thence by conductor-pin X to conductor-ring U' on disk U , to spring contact or brush W^2 , through the motor-windings to binding-post a^6 and switch X , 95 back to the source.

The apparatus as thus described operates as follows: While a line is being written the several parts occupy the relation shown in Fig. 1, and drum E is clutched to gear F by 100 coöperating pins h and h' , as hereinbefore described. As each key is struck the drum E draws the carriage, by means of the band e^2 , from the right to the left hand side of the type-writing machine step by step under the 105 influence of spring f^8 . During this operation pinion t^4 and gear t^8 idle upon shaft t . When it is desired to return the carriage to the beginning of the line, the operator presses upon the return-key connected with the key-lever 110 b^7 , which by means of link b^6 and lever b^5 brings the crescent-shaped trip c^5 against the pin h' thus throwing said pin out of engagement with the pin h and locking said pin h' out of engagement by means of latch N^2 . The 115 pin h is at once carried beyond the pin h' , and the drum E is now free to move in a direction contrary to its former path of revolution, in the return of the carriage. The downward movement of lever b^5 causes link R' to rock 120 bell-crank lever R to force shaft t toward the rear of the machine, thereby engaging the 125

clutch-faces of pinion t^4 and gear t^5 and causing latch N to engage the notch t^6 in said shaft and hold the latter in its operative position. The wheel F continuing to revolve under the tension of spring f' drives the gear t^8 through its clutch engagement with t^4 in a direction to reverse the carriage and return the latter to its initial position by means of rack G, which is in mesh with said gear t^8 . The gears t^8 and rack G, therefore, constitute a reversing-gearing for the carriage. As said gear t^8 is positively driven pawl t^7 , engaging ratchet t^6 , causes gear t^4 to rotate on shaft t and to impart a movement of rotation to disk C, with the result that pin X, which rests upon insulating-block W, passes into contact with the conductor-ring V and the circuit to the motor A is closed, thereby causing the latter to start instantly and impart a movement of rotation to shaft B in such direction as to rewind spring f' , and thereby restore the tension of the propelling-motor. As soon as the carriage has reached its initial position the reversing-gearing and, accordingly, gears t^4 and C, are arrested in their movement; but the motor A continues to revolve until pin X engages insulating-block W', which arrests and materially reduces the speed of the motor, which, however, is given an additional impulse as said pin X passes off of said block W', the motor being finally brought to rest when said pin X engages the second fiber block W, at which time the winding apparatus is restored to its original condition, as illustrated in Fig. 1. Just before the return movement of the carriage is completed, however, the end of latch N strikes the depending end of latch N and throws the latter out of engagement with the notch in shaft t , thereby permitting spring t^6 to draw said shaft forward and disengage the coöperating clutch-faces of pinion t^4 and gear t^5 , so that the machine is ready for a continuation of the writing operation as soon as the carriage has been returned to its initial position.

The return-key as designed provides for the return of the carriage at any point of the line beyond, say, "20" of the scale. When it is desired to return the carriage at a position nearer the beginning of the line, it has been found most convenient to do so by hand, though the same method of return can be used at any point by slightly changing the size of the crescent-shaped trip c^5 .

In practice an automatic return at some fixed point has been found to be less convenient than the use of a return-key. Consequently there has been no attempt in the present apparatus to provide for such automatic movement.

It is to be observed that the operation of propelling the carriage in both directions is accomplished by a single motor that is connected directly to the carriage for the forward speed and that is coupled to the car-

riage by a reversing-gearing for the return movement of the carriage and that the operation of disconnecting said motor from the forward feeding relation and simultaneously connecting it with the reversing mechanism likewise throws into operation the electric motor A, which operates while the carriage is being returned and until the energy of the spring-motor has been exactly restored. By this arrangement it is only necessary to provide a spring-motor having power a little in excess of that necessary to feed the carriage forward during the printing operation, and by coupling a train of reducing-gearing between the electric motor and the spring-drum of the propelling-motor the energy of the power-storing mechanism—namely, the electric motor required to wind the spring of the propelling-motor—is reduced to a minimum, measured at any instant during its operation. The whole apparatus is, therefore, exceedingly simple in construction and efficient in operation and is capable of being applied and operated by any person skilled in the operation of type-writing machines.

Having thus described my invention, what I claim is—

1. A type-writer having a paper-carriage, a motor for propelling said carriage in its advance and return movements, reversing-gear adapted to connect the motor and the carriage for reversing the said carriage, a second motor for restoring the energy of the first-mentioned motor, and mechanism actuated by the reversing-gear to start said second motor when the carriage begins its reverse movement; substantially as described.

2. A type-writer having a paper-carriage, a motor having a unidirectional rotation for propelling said carriage in its advance and return movements, mechanism for advancing the carriage step by step, reversing-gear adapted to connect the motor and the carriage for reversing said carriage, means for simultaneously disconnecting the advancing mechanism and connecting the reversing-gear and the carriage, a second motor for restoring the energy of the first-mentioned motor, and mechanism actuated by the reversing-gear to start said second motor when the carriage begins its reverse movement; substantially as described.

3. A type-writer having a paper-carriage, a motor having a unidirectional rotation for propelling the carriage in its advance and return movements, mechanism for advancing the carriage step by step, reversing-gear adapted to connect the motor and the carriage for reversing said carriage, means for simultaneously disconnecting the advancing mechanism and connecting the reversing-gear and the carriage, a second motor for restoring the energy of the first-mentioned motor, and mechanism actuated by the reversing-gear to start said second motor; substantially as described.

4. A type-writer having a paper-carriage, a motor having a unidirectional rotation for propelling said carriage in its advance and return movements, mechanism for advancing the carriage step by step, reversing-gear adapted to connect the motor and the carriage for reversing said carriage, means for simultaneously disconnecting the advancing mechanism and connecting the reversing-gear and the carriage, an electric motor geared to said first-mentioned motor for restoring the energy thereof, and a circuit-controller for the electric motor to start the said electric motor and stop the same when the energy of the first motor has been restored; substantially as described. 5 10 15 20 25
5. A type-writer having a paper-carriage, a motor having a unidirectional rotation for propelling said carriage in its advance and return movements, mechanism for advancing the carriage step by step, reversing-gear adapted to connect the motor and the carriage for reversing said carriage, means for simultaneously disconnecting the advancing mechanism and connecting the reversing-gear and the carriage, an electric motor geared to said first-mentioned motor for restoring the energy thereof, and a circuit-controller for said electric motor operatively connected with the reversing-gear to start the electric motor and to stop the same when the energy of the first motor has been restored; substantially as described. 20 25 30 35 40 45 50
6. A type-writer having a paper-carriage, a toothed power-wheel having a unidirectional rotation for propelling said carriage in its advance and return movements, a band-wheel adjacent to said power-wheel and connected to the carriage for advancing the latter, coöperating clutch members on the power-wheel and the band-wheel, mechanism for disengaging said clutch members, reversing-gear driven by said toothed wheel for reversing said carriage, connections between said reversing-gear and the clutch-disengaging mechanism for throwing the reversing-gear into operation, an electric motor for restoring the energy of said power-wheel, and a circuit-controller for the electric motor to start the said electric motor and to stop the same when the energy of the power-wheel has been restored; substantially as described. 35 40 45 50 55 60 65
7. A type-writer having a paper-carriage, a toothed power-wheel having a unidirectional rotation for propelling said carriage in its advance and return movements, a band-wheel adjacent to said power-wheel and connected to the carriage for advancing the latter, coöperating clutch members on the power-wheel and band-wheel, mechanism for disengaging said clutch members, reversing-gear driven by said toothed wheel for reversing said carriage, connections between said reversing-gear and the clutch-disengaging mechanism for throwing the reversing-gear into operation, an electric motor for restoring the energy of said power-wheel, and a circuit-controller for the electric motor to start the said electric motor and to stop the same when the energy of the power-wheel has been restored; substantially as described. 55 60 65 70 75 80 85 90 95 100 105 110 115 120 125 130
8. A type-writer having a paper-carriage, a power-wheel mediateely coupled thereto for propelling the carriage in its forward movement, means for coupling the power-wheel and the carriage to reverse the latter, a motor connected with the power-wheel to restore the energy of the latter, trip mechanism for disengaging the forward driving-coupling and engaging the reverse driving-coupling, and means actuated by the reverse driving-coupling to start the energy-restoring motor when the carriage begins its reverse movement and to stop said motor when the energy of said power-wheel has been restored; substantially as described. 70 75 80 85 90 95 100 105 110 115 120 125 130
9. A type-writer having a paper-carriage, a power-wheel mediateely coupled thereto for propelling the carriage in its forward movement, means for coupling the power-wheel and the carriage to reverse the latter, an electric motor connected with the power-wheel to restore the energy of the latter, trip mechanism for disengaging the forward driving-coupling and engaging the reverse driving-coupling, and means actuated by the reverse driving-coupling to close the circuit of the electric motor and to open the same when the energy of said power-wheel has been restored; substantially as described. 90 95 100 105 110 115 120 125 130
10. A type-writer having a paper-carriage, a power-wheel mediateely coupled thereto for propelling the carriage in its forward movement, reversing-gear for coupling the power-wheel and the carriage to reverse the latter, an electric motor connected with the power-wheel to restore the energy of the latter, trip mechanism for disengaging the forward driving-coupling and engaging the reverse driving-coupling, and a rotary circuit-controller actuated by the reversing-gear to start the electric motor when the carriage begins its return movement and to stop said motor when the energy of said power-wheel has been restored; substantially as described. 105 110 115 120 125 130
11. A type-writer having a paper-carriage, a power-wheel mediateely coupled thereto for propelling the carriage in its forward movement, reversing-gear for coupling the power-wheel and the carriage to reverse the latter, said reversing-gear comprising a longitudinally-sliding shaft, a clutch-gear revolubly mounted upon said shaft and driven from said power-wheel, a second clutch-gear on said shaft to be operatively engaged by said first gear, a rack on said carriage meshing with said latter clutch-gear, an electric motor connected with the power-wheel to restore 120 125 130

the energy of the latter, trip mechanism for
disengaging the forward driving-coupling
and simultaneously coupling the clutch-gears
to reverse the movement of the carriage, a
5 rotary circuit-controller actuated by the re-
versing-gear to start the electric motor when
the carriage begins its return movement and
to stop said motor when the energy of said

power-wheel has been restored; substantially
as described. 10

In testimony whereof I affix my signature
in presence of two witnesses.
